UNITED STATES PATENT OFFICE

WILLIAM W. DANTOW, OF CHICAGO, ILLINOIS.

MECHANISM FOR OPENING DOORS OF FREIGHT-CARS.

1,081,294.

Specification of Letters Patent. Patented Dec. 16, 1913.

Application filed June 27, 1912. Serial No. 776,158.

To all whom it may concern:

Be it known that I, WILLIAM W. DANTOW, a citizen of the United States, and a resident of the city of Chicago, county of Cook, and State of Illinois, have invented certain new and useful Improvements in Mechanism for Opening Doors of Freight-Cars, of which I do declare the following to be a full, clear, and exact description, reference being had to the accompanying drawings, forming part of this specification.

It is common practice to provide the sliding doors of freight cars with wedging devices at their tops and bottoms so that as a door is moved to closed position, it will be forced more closely against the frame of the door so as to avoid leaving space around the edges of the door through which cinders, dust, rain, etc., may pass into the car. The serious difficulty encountered with the use of such devices for effecting the closing of the doors is that the doors are apt to become so tightly wedged that crowbars or like instruments are often used for initially forcing the doors open, thus seriously marring the doors and the door-posts.

The present invention has for its object to provide a simple and effective means whereby the initial opening of the door may be readily effected without marring the parts, and to this end the invention consists of the novel features hereinafter described, illustrated in the drawings and particularly pointed out in claims at the end of this specification.

Figure 1 is a view in side elevation showing a portion of a car door and the left-hand front post of the door-jamb showing my invention applied thereto, the door being shown in closed position. Fig. 2 is a view showing the door partially open and showing parts of the operating lever broken away. Fig. 3 is a view in horizontal section through the door and door-post, the section being taken immediately above the door-opening mechanism. Fig. 4 is a view in vertical section on line 4-4 of Fig. 1, showing the operating mechanism in elevation.

The door 1 may be of any usual or suitable construction and will be equipped, with any usual or suitable devices whereby it may slide freely toward and away from the door-post 2 that projects from the side wall 3 of the car. Upon the door-post 2 is mounted a stop-plate 4 that is suitably connected to

the door-post, as by bolts 5. This stop-plate 4 has an outwardly projecting member 6 between which and the stop-plate 4 extends a brace-rib 7.

Upon the door 1 is mounted an operating lever 8, the inner end of which is provided with a cam-shaped portion 9 adapted to bear against the outwardly projecting portion 6 of the stop-plate 4. The operating lever 8 is formed with a handle 10 whereby it may be conveniently manipulated, a portion of this handle being broken away in the drawings. Preferably, the operating lever 8 is a malleable casting and to strengthen this lever, it is provided upon its outer surface with a rib 11 and upon its inner face with a rib 12 (see Fig. 4). The operating lever 8 is also formed with an opening adapted to receive a boss 13 that projects from and is preferably formed integral with a plate 14 that is shown attached to the door 1.

The attachment of the plate 14 to the door is preferably effected by means of two bolts 15 and 16, the bolt 15 passing through an opening in the boss 13, while the bolt 16 passes through a suitable opening formed adjacent the outer end of the plate 14. A washer 15 is between the head of the bolt 15 and the operating lever serves to retain the operating lever in position upon the boss 13. The openings in the plate 14 to receive the bolts 15 and 16 are preferably square openings, and that part of each of the bolts 15 and 16 adjacent their heads is correspondingly shaped, so that when the bolts 15 and 16 are in position, as shown in the drawings, the bolts cannot be removed from the outside of the door, the inner ends of the bolts being retained by suitable nuts 17 and 18 on the inner side of the door (see Fig. 3).

Normally, the operating lever 8, when the door is closed, occupies the vertical position shown in Fig. 1 of the drawings, the cam-shaped end of the lever being against, or approximately against, the outwardly projecting portion 6 of the stop-plate 4. If, now, it is desired to effect the initial opening of the door, the attendant will grasp the handle of the operating lever and swing the lever in the direction of the arrow (Fig. 1) to the position shown in Fig. 2, thereby causing the cam-shaped end 9 of the lever to bear against the part 6 of the stop-plate 4 and pry the door from the closed position shown in Fig. 1 to the partially open position shown in Fig. 2.

2
Preferably, the plate 14 is provided with an outwardly projecting stop 19 to arrest the upward movement of the operating lever, this stop being adapted to contact with the rib 12 upon the inner face of the lever, as shown in Fig. 2 of the drawings. When the initial opening of the door has been effected, the attendant will release the operating lever, when it will return automatically to the vertical position shown in Fig. 1.

While I have shown the operating lever as mounted upon the door and the plate 4 with which the lever co-operates as mounted upon the front post of the door, it is obvious that the location of the parts may be varied without departing from the spirit of the invention, and the precise details of the construction above set out may also be varied by the skilled mechanic without departure from the scope of the invention.

Having thus described my invention, what I claim as new, and desire to secure by Letters Patent, is—

25 1. The combination with a car door and its frame, of a stop plate mounted upon one of said parts and an operating lever pivot-

ally mounted upon the other of said parts, said operating lever being provided with a cam-shaped projection to contact with said stop plate, the weight of said operating lever being arranged to normally hold the parts of said lever at one side of the edge of the part whereon the lever is mounted to avoid obstructing the door opening. 35

2. The combination with a car door and its frame, of a stop plate mounted upon one of said parts and an operating lever pivotally mounted upon the other of said parts, said operating lever being provided with an end projecting beyond its pivot to contact with said stop plate, a plate having formed integrally therewith a boss passing through said operating lever and a stop to engage said lever, and a retaining bolt passing through said lever and said boss, said lever being arranged so that when in normal position all parts thereof shall be at one side of the edge of the part whereon the lever is mounted. 40 45
